(57) **CLAIM**

The ornamental design for a microwave heating bowl, as shown and described.

DESCRIPTION

FIG. 1 is a perspective view of a microwave heating bowl, showing the first embodiment of my new design;

FIG. 2 is another perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof;

FIG. 8 is a perspective view of a microwave heating bowl, showing the second embodiment of my new design;

FIG. 9 is another perspective view thereof;

FIG. 10 is a front elevational view thereof;

FIG. 11 is a rear elevational view thereof;

FIG. 12 is a left side view thereof; and,

FIG. 13 is a right side view thereof.

1 Claim, 11 Drawing Sheets
